UNITED STATES PATENT OFFICE.

CARL L. OLSEN, OF INDIANAPOLIS, INDIANA, ASSIGNOR TO E. C. ATKINS AND COMPANY, OF INDIANAPOLIS, INDIANA, A CORPORATION OF INDIANA.

SAW-SWAGE.

1,074,010.

Specification of Letters Patent. Patented Sept. 23, 1913.

Application filed November 16, 1912. Serial No. 731,838.

To all whom it may concern:

Be it known that I, CARL L. OLSEN, a citizen of the United States, residing at Indianapolis, Marion county, and State of Indiana, have invented and discovered certain new and useful Improvements in Saw-Swages, of which the following is a specification.

My invention relates to saw swages and its object is to provide means of a strong and simple construction for adjusting the swage for the purpose of obtaining a greater or less degree of swaging action on the saw teeth or to adapt the anvil and die to teeth having different angles and at the same time to effect such end without decreasing the strength of the block in which the operative parts are mounted.

To this end my invention is embodied in preferable form in the device hereinafter described and illustrated in the accompanying drawings.

In these drawings Figure 1 is a side view in elevation of the device showing the same applied to a saw; Fig. 2 a top plan view; Fig. 3 a longitudinal vertical section on the line 3—3 of Fig. 2; Fig. 4 a vertical section at right angles to Fig. 3 on the line 4—4 of Fig. 3; Fig. 5 a detail plan of the anvil, as seen from the dotted line 5—5 in Figs. 3 and 4, the adjusting member therefor and the controlling member for said adjusting member arranged in the relative position which they are adapted to occupy on the swage block but detached from said block; Fig. 6 a perspective view of the parts shown in Fig. 5; Fig. 7 a detail view of the inner end of the controlling member, and Fig. 8 a detail of a swaged saw tooth.

Referring to the drawings, 1 is a saw to which is adapted to be rigidly secured by means of clamps 2, an arm 3 at one end of a frame or carrier 4, the opposite end of which carrier or frame is provided with an arm 5 carrying a guide plate 6. Adjustably attached to the frame is a substantially cylindrical swage block 7 which is adjustable in a rotatable direction to permit the proper positioning of the die and anvil with respect to the tooth to be swaged. A guide ear 8 secured on the block takes over the edge of the frame. Clamping screws 9 extend through the frame and into the block enabling the block and frame to be rigidly clamped together after the desired adjust-

ment has been obtained, elongated slots being provided in the frame to permit of such adjustment. By means of a screw bolt 10 which is screwed into the block and which has an operating lever 11, the block may be rotated with respect to the frame and saw to obtain the desired adjustment.

Extending transversely through the block is a swaging shaft 12 to one end of which is secured an operating lever 13. Intermediate the ends of this shaft there are formed on the surface thereof die faces 14 one of which is adapted to be forced against the lower side of a tooth to effect the swaging action.

Extending vertically entirely through the swage block is a screw hole and socket 15 having the upper portion thereof threaded to receive an anvil screw 16. Below this closing screw is adapted to be held the oblong anvil 17, the flat surface of one of the shorter faces of which is adapted to rest squarely against the upper edge of the saw tooth when the anvil has been adjusted to correct position for the swaging operation. This anvil has its greater length extending above the upper edge of the article to be swaged. This anvil fits within and is embraced on three sides by the walls of a slot 18 cut in the edge of a cylindrical sliding carrier bolt 19 which constitutes the adjusting member for the anvil. This bolt is mounted slidably in a socket extending substantially diametrically of the swage block and entering the anvil socket hole, and the bolt extends across the anvil socket. At the end opposite the slot 18 and on a portion of the periphery of the slide bolt opposite the said slot is formed a second vertical open slot 20 with which is adapted to engage a pin 21 projecting eccentrically from the end of a short cylindrical stud shaft 22 which is mounted in a socket extending from the outer face of the block into the socket provided for the slide bolt.

The stud 22 is provided on its outer end, outside the face of the block, with a suitable polygonal head 23, whereby it may be turned through the engagement of a suitable wrench. Surrounding the edge of the outer end of the socket in which this stud is mounted is a series of graduated numbers 24 with which is adapted to register a notch 25 cut in the head of the shaft. These numbers constitute an indicating scale by which the extent of movement desired to be given

to the operating stud may be determined, for the purpose of regulating through the movement of said stud, the relative distance between the die and anvil. Set screws 26, 5 27, extend from the opposite faces of the block into the anvil socket 15, and their ends are adapted to be forced against the opposite flat sides of the anvil so as to hold the latter rigidly but adjustably in its socket.

10 A set screw 28, extends into the block from one face thereof and enters the socket of the slide bolt 19 and is adapted to bear against a flattened portion 29 of said bolt for the purpose of locking the latter rigidly in place after it has been adjusted.

15 In the operation of the device the anvil set screw 27 is loosened, so as to leave the anvil free to move laterally, and then the set screw 28 is loosened to release the adjusting slide bolt and the operating stud 22 20 is turned until the notch on its head registers with the number that corresponds to the particular shape of the tooth to be swaged and the depth of metal to be upset. The turning of the stud through the engagement 25 of the eccentric pin with the slot 20 carries the slide bolt in or out, thus moving the anvil diametrically toward or away from the die, thus accommodating the space between the die and anvil to a less or greater acuteness of the point of the saw, and to obtain a less or greater degree of swaging action. The set screws 27 and 28 are then tightened and the anvil screw 16 adjusted so as to 30 force the anvil downward in its socket to the proper distance from the die to admit the saw tooth. The saw is then clamped to the frame, the tooth to be swaged being admitted through the opening in the bottom 35 of the block into the space between the die and anvil. The block is then adjusted by means of the operating lever 11 to clamp the lower flat face of the anvil squarely against the upper edge of the saw tooth. After the 40 anvil has been set to the required adjustment the swaging handle 13 is turned so as to carry the die against the under face of the tooth, thus pressing the metal of the tooth against the anvil and swaging the tooth to 45 the degree permitted by the distance between the die and anvil.

50 It will be seen that with my invention the strength of the cylindrical block is maintained substantially intact since the only part of the metal that is required to be cut away to accommodate the operative adjusting members is that necessary for the central anvil socket, the sliding bolt socket and the socket for the eccentric stud. The 55 lateral adjustment of the anvil in connection with the positioning of the anvil with its greater length extending vertically above the edge of the article to be swaged enables a considerable degree of adjustment to be 60 obtained with a slight movement of the 65

swaging block, thus obviating the necessity of having a large saw engaging slot in the block for the purpose of permitting adjustment through a long arc. By means of the projection of the headed operating stud beyond the face of the plug, such shaft may not only be readily operated by means of an ordinary wrench but also such projection serves in conjunction with the indicating scale on the face of the block to permit of the adjustment of the stud and of the anvil to any predetermined and desired degree without the necessity of cutting away the block so as to expose the die and anvil to view. By limiting the adjustability of the parts to the anvil it is rendered possible to operate the die without danger of altering the adjustment by the rotation of the die during the swaging operation.

Having thus described my invention, what I claim is:

1. In a swaging device, the combination with a block of a die rotatably mounted in said block, an anvil adjustable in a line parallel with its swaging face with respect to said die and positioned in said block to have its greater length at an angle to and extending upwardly from the effective swaging face of the die, a sliding member in said block engaging said anvil, and means for adjusting said sliding member, substantially as described.

2. In a swaging device, the combination with a block of a rotatable die mounted therein, an anvil adjustable in a line parallel to its swaging face with respect to the die, and a sliding member in said block engaging to adjust said anvil in said line, said sliding member being mounted in said block above the axis of rotation thereof and movable laterally, substantially as described.

3. In a swaging device, the combination with a block of a rotatable die, an anvil adjustable in a line parallel with its swaging face with respect to the die, a slidable member mounted within said block and having means to engage positively said anvil and means to operate said slidable member, substantially as described.

4. In a swaging device, the combination with a swaging block of a die mounted therein, an anvil mounted in said block and adjustable toward and away from said die in a line parallel to the swaging face of the anvil, a sliding bolt in said block having means to positively engage said anvil and a member having means to engage said bolt at one end and extending through the block at the outer plane face thereof at the other end and operable to move said bolt laterally to adjust the anvil with respect to the die, substantially as described.

5. In a swaging device, the combination with a block of a die rotatably mounted therein, an anvil movable toward and from

- 5 said die laterally and angularly with respect to the axis of rotation of the latter, a sliding bolt having means to engage said anvil and mounted within said block in a socket extending angularly to said axis of rotation and also angularly to said anvil and a rotatably operable member extending into the block at right angles to said bolt and adapted to engage the latter, said member having 10 means to slide said bolt toward or from said die, substantially as described.
6. In a swaging device, the combination with a swaging block of an anvil and a die mounted within said block, said block having 15 a socket to receive said anvil and having a socket at an angle to the first socket, a sliding bolt mounted within said socket and slotted to engage said anvil, a rotatably operating member extending into said block 20 at right angles to the second socket and entering the latter, said member having an eccentric pin adapted to engage a slot in said sliding bolt, substantially as described.
7. In a swaging device, the combination 25 with a swaging block of a rotatable die and an anvil in said block adjustable laterally toward and from said die in a line parallel to the swaging face of the anvil to vary the swaging action, means engaging said anvil
- and operable to move the same with respect 30 to the die, controlling means operable from the outside face of the block to operate said anvil moving means, and indicating means on the face of the block with which said controlling means are adapted to register for 35 the purpose of enabling the extent of adjustment of said anvil to be determined, substantially as described.
8. In a swaging device, the combination with a swaging block of a rotatable die and 40 an anvil in said block adjustable laterally toward and from said die in the line parallel to the swaging face of the anvil, a stud having a head mounted on the outer plane 45 face of the block, operative means between said stud and said anvil and a scale on the said outer face of the block with which an indication on said head is adapted to register to enable the adjustment of the anvil to be regulated, substantially as described. 50

In witness whereof, I have hereunto set my hand and seal at Indianapolis, Indiana, this first day of November, A. D. nineteen hundred and twelve.

CARL L. OLSEN. [L.S.]
